(57) **CLAIM**

We claim the ornamental design for a tray holder with hand grips, as shown and described.

DESCRIPTION

FIG. 1 shows a perspective view of the tray holder with hand grips of our invention.

FIG. 2 shows a side elevation view of the tray holder.

FIG. 3 shows a bottom plan view of the tray holder; and, FIG. 4 shows a view of the tray holder in use for exemplary purposes.

The broken line showing environmental structure in FIG. 4 is for illustrative purposes only and forms no part of the claimed design.
